UNITED STATES PATENT OFFICE.

STEPHEN KATKÓ, OF AHMEEK, MICHIGAN.

LIFE-SAVING BOAT.

1,101,287.

Specification of Letters Patent. Patented June 23, 1914.

Application filed January 29, 1914. Serial No. 815,232.

To all whom it may concern:

Be it known that I, STEPHEN KATKÓ, a subject of the King of Hungary, residing at Ahmeek, in the county of Keweenaw and 5 State of Michigan, have invented certain new and useful Improvements in Life-Saving Boats, of which the following is a specification.

This invention relates to life saving boats. 10 The object of the invention is to provide a boat of this character which will not only secure the maximum of assurance against capsizing, but will insure comfort and security to rescue cast-aways.

15 With the above and other objects in view, as will appear as the nature of the invention is better understood, the same consists in the novel construction and arrangement of parts of a life-saving boat, as will be hereinafter 20 fully described and claimed.

In the accompanying drawings forming a part of this specification, and in which like characters of reference indicate corresponding parts: Figure 1 is a view in perspective 25 of a life-saving boat constructed in accordance with the present invention. Fig. 2 is a view in vertical longitudinal section. Fig. 3 is a transverse sectional view taken on the line 3—3 of Fig. 2, and looking in the direction of the arrow thereon. Fig. 4 is a similar view taken on the line 4—4, Fig. 2. Fig. 5 is a transverse sectional view showing a slightly modified form of construction.

The boat comprises as usual, a hull 1 which is covered approximately from end to end by a roof 2, the stern of the boat being closed by a stationary bulk head 3, and the bow by a slidable bulk head 4. At the stern, the hull is extended beyond the bulk head 3 to provide a flooring 5 from which arises a wall 6 extending the width of the boat and provided with an inclined roof 7. Within the compartment formed by the bulk head 3 and the wall 6 is arranged a seat 8 designed to accommodate the persons who will propel the boat, and to effect this latter result, two paddle wheels 9 are provided which are connected by a shaft 10, the latter being provided intermediate of its ends with a 45 crank 11 that is designed to be grasped by the hands of the operators to drive the propellers. The bulk head 3 is provided with an opening 11a through which it is designed that food should be passed from the interior 50 of the boat to the persons operating the propellers. In order to protect the operators

from wave action which would tend to flood the compartment in which they are located, there is a deflector 12 provided, which will extend the width of the boat, and is of curvilinear form, the curve being downward, the deflector being pivotally-mounted upon a shaft 13 which is journaled in bearing boxes 14 carried by the sides of the boat. The deflector is provided with a downward projecting extension 15 carrying adjacent to its lower end an eye 16, with which is connected one end of a coiled spring 17, the other end of which is connected with an eye 18 secured to the strain of the boat adjacent to the keel. The interior of the boat is provided with a floor 19 and with side benches 20 to accommodate rescued cast-aways, a stove 21 being provided for the purpose of heating the interior of the boat. The slidable bulk head 4 is mounted between walls 22 forming the bow of the boat, and on each side of the bulk head are furnished seats 23 designed to be occupied by oarsmen, the oars being thrust through openings 24 formed in the sides of the boat and engage with oar-locks 25 of the usual or any preferred construction. The bow of the boat is provided with an extension 26 upon which is mounted a standard 27 carrying a vane 28 upon which is mounted a lantern 29, the vane operating always to cause the light to be projected in advance of the bow.

One of the essential features of the invention resides in the means for preventing the boat from capsizing, and this consists in the employment of two equilibrators 30 which are hollow, and are preferably constructed of metal, and are hinged upon shafts 32 carried by brackets 33 secured to the sides of the boats. These equilibrators are connected by cables or chains 34, one being shown in Fig. 3, which pass around grooved sheaves 35, carried by hangers 36 secured to the bottom of the boat, the ends of the cables or chains 37 being secured to eyes 37 secured to the under sides of the equilibrators adjacent to each end thereof. In order to brace the equilibrators against strains due to wave action, additional cables 38 are employed, which are secured at one end to eyes 39 disposed at the front end of the equilibrators on their upper sides, the other ends of the cables being secured to a cross-piece 40 secured to the extension 26 in advance of the standard 27. The equilibrators are connected by curved rocking beams 41, the terminals of which

are secured between brackets 42 secured to the upper sides of the equilibrators. The intermediate portions of the rocking beams are pivoted to one end of a pair of links 43, the other ends of which are pivoted to standards 44 secured to the upper side of the roof. From this arrangement, it will be seen that should the boat rock to the right, the contact of the equilibrator on the right side of the waves will cause it to be raised and thus transmit the motion through the rocking beams to the equilibrator on the left side, which will be depressed, and thus in position to meet the waves when the boat rocks in that direction. By the provision of the equilibrators, it will be seen that it will be practically impossible for the boat to capsize, inasmuch as by the employment of these equilibrators an extended area is presented to the action of the waves which will practically preclude any danger of capsizing, and furthermore, these equilibrators will operate in a manner that will be perfectly obvious, to maintain the stability of the boat in the roughest water.

The form of rocking beams shown in Figs. 1, 2, and 3, are constructed of metal, and in one piece, but if preferred, wood may be employed in lieu of metal, and when such construction is adopted, the rocking beam 45 will be constructed as shown in Fig. 5, being straight, and carrying at its terminals, links 46 which are pivotally-connected with the

equilibrators in the same manner as that shown in Figs. 1-3.

From the foregoing description, it will be seen that although the improvements herein defined are simple in character, they will co-operate in the production of a thoroughly useful and efficient form of life-boat, and one which will present points of novelty not heretofore present in the life-boats of ordinary construction.

What I claim as new is:—

1. The combination with a life boat, of buoyant equilibrators pivotally-connected to the sides thereof, rocking beams pivotally-connected with the equilibrators, sheaves carried by the bottom of the boat, and flexible connections between the equilibrators and engaging the sheaves.

2. The combination with a life boat having a roof, of standards carried by the roof, links pivotally-connected to the standards, buoyant equilibrators pivotally connected to the sides of the boat, rocking beams pivotally connected with the links and with the equilibrators, and flexible connections between the equilibrators.

In testimony whereof I affix my signature in presence of two witnesses.

STEPHEN KATKÓ.
